UNITED STATES PATENT OFFICE.

GEORGE FREDERICKS, OF ST. PAUL, MINNESOTA, ASSIGNOR TO SWIFT & COMPANY, OF CHICAGO, ILLINOIS, A CORPORATION OF ILLINOIS.

BARREL-HEADING MACHINE.

Application filed August 3, 1927. Serial No. 210,355.

This invention relates to barrel heading machines of the type employing suction means for handling the heads.

The main objects of this invention are to provide improved means for maintaining the suction head of the machine in a substantially horizontal plane during its movement in picking up the barrel head and placing it in the end of the barrel being headed; to provide improved means for compressing the barrel staves during and subsequent to the heading operation; and to provide improved leverage means for forcing the barrel head into the barrel.

An illustrative embodiment of the invention is shown in the accompanying drawings wherein:—

Fig. 1 is a side elevation of the machine with the barrel being worked upon, and suction head when inserting a head therein, shown in dotted outline.

Fig. 2 is a front elevation of the machine.

Fig. 3 is a top plan view of the same.

Fig. 4 is a sectional view taken on line 4—4 of Fig. 1.

Fig. 5 is a sectional detail taken on the line 5—5 of Fig. 1.

In the present barrel heading machine which is the subject matter of this application, the suction head is mounted so as to be in a horizontal plane at all times. At the same time, it is shiftable vertically and swingable sidewise, the head maintaining its horizontal position, however, throughout such movement.

The advantage of this construction is that the chime in the upstanding ends of the barrel staves forms an annular horizontally disposed groove for receiving the beveled edge of the barrel head, and when the suction head which carries the barrel head is lowered into the upper end of the barrel being worked on, the barrel head will automatically be in correct angular position to fit into the chime without necessitating rocking or shifting of the suction head to bring it to a horizontal plane. With this construction, considerable time is saved and, of course, that means a reduction in manufacturing cost.

In the construction shown in the drawings, a suitable frame work 1, preferably formed of angle irons, supports a vertically disposed cylinder 2 which communicates at its upper and lower ends with suction pipes

3 and 4 respectively, which join a main suction pipe 5.

A sleeve 6 surrounds the cylinder 2 in spaced relation thereto and is vertically slideable thereon. The medial portion of the cylinder 2 is provided with an aperture 10 through the wall thereof for providing communication between the interior of the cylinder 2 and the sleeve 6. The sleeve 6 in turn has rigidly attached thereto a rectangular shaped duct 11 which communicates with the interior of the sleeve 6. The duct 11 is attached to and communicates with a vertically disposed tubular duct 12, which is closed at its upper end 13 and carries an inverted funnel shaped suction head 14 on the lower end thereof.

An operating handle 15, having a bifurcated shank 16 which embraces opposite sides of the duct 12 is pivoted thereto at 17 adjacent the lower end thereof. A prize bar 18 is slidably mounted between the side arms of an inverted U-shaped bracket 19 near one end thereof and the other end thereof is bifurcated to likewise embrace the duct 12, the bifurcated arms thereof being pivotally attached to the bifurcated arms 16 of the handle 15 at the point 20. A coil tension spring 21 which has one end thereof attached to the bar 18 and the other end thereof to a clip 19' fastened to the head 14, is provided for normally holding the bar 18 in the position shown in Fig. 1 of the drawings. An inverted V-shaped bracket 22 is rigidly mounted on the framework 1 for receiving the outer tip end of the bar 18 when the bar is shifted endwise by movement of the handle 15 about its pivot 17 to a horizontal position. In this manner the bar 18 and the bracket 22 serve to bring the suction head and the barrel top held thereon into registration with the open end of the barrel. When the handle 15 is rotated to the position shown in dotted lines in Fig. 1, the bar 18 is moved relative to the bracket 19 and into the guide bracket 22, and the handle is restrained from further rotation by the engagement of the right hand end portion of the bar 18 with the pivot pin 17 of the bifurcated shank 16. When further pressure is applied on the handle, the suction head 14 together with the ducts 11 and 12 are moved downwardly for engaging the barrel head on the end of the barrel.

Means are provided for aiding and assist-

ing in the manual raising and lowering of the unit which comprises the sleeve 6, duct 11, duct 12 and suction head 14 carried thereby and comprise a pair of ropes or cables 25 and 26, each of which has one end attached to eye-bolts 27 and 28 respectively, which in turn are secured to a plate 29 which forms the lower closure of the sleeve 6. The opposite ends of the cables 25 and 26 pass upwardly and over pulley wheels 33 and 34 respectively and then downwardly within vertical tubes 35 and 36 respectively, the lower ends of each being attached to counter-weights 37 which are slidably housed within the tubes 35 and 36. A similar plate 30 forms a closure for the upper end of the sleeve 6 and both closures are provided with openings therethrough for receiving the vertically disposed rods 31 and 32 which provide guideways for the unit.

Means are provided for drawing together the upstanding ends of the staves of the barrel being headed and comprise a flexible cable 40 having its ends anchored at 41 to the framework and the medial portion thereof formed in a loop which is adapted to be placed around the upper ends of the barrel staves. The two sides of the looped cable 40 pass through the medial portion of a member 42 which carries a pair of pulley wheels 43 and 44 pivotally mounted thereon for bearing against the cable 40.

The member 42 is horizontally slidable on the framework 1 toward and away from the barrel being worked upon and movement thereof is controlled by a foot lever 46 pivoted at one end 47 to the supporting frame 1 and provided with a coil tension spring 48 which bears between the frame and the lever for normally holding it in a substantially horizontal position. Lever 46 has a vertically disposed link 49 pivotally attached thereto, the upper end of which is pivotally connected at 50 to one end of each of links 51 and 52. The opposite end of link 51 is pivoted at 53 to the framework 1 and these links, when in operative position are in the form of an inverted V as shown in Fig. 1 of the drawings. Link 52 has its other end connected to the member 42 so as to shift the same horizontally toward the barrel being worked upon when the foot lever 46 is depressed. The outer or bearing face of member 42 is arcuate so as to conform to the outer periphery of a barrel being headed as shown particularly in Figs. 3 and 4 of the drawings.

The framework 1 is formed so as to provide a table 60 for supporting a pile of barrel heads 61 preparatory to their being placed in the barrels being headed. An upstanding semi-circular guide retaining member 63 is provided on the table 60 for keeping the supply of barrel heads in position thereon.

In the operation of this machine, a stack

of barrel heads is piled on the table 60 and the suction fan (not shown) which is connected to the duct 5, is started. This causes the air to be drawn in through the suction head 14 which, with ducts 12, 11 and sleeve 6 operate as a unit. A barrel is placed in position and the cable 40 placed therearound, and partially drawn tight by depressing the foot lever. The suction head unit is then swung over to the supply of barrel heads and lowered down against the top head. The suction lifts this barrel head from the pile when the head is raised and it is then swung about a vertical axis until it is directly above the barrel being headed, at which time the handle 15 is pulled downwardly into a substantially horizontal position. This movement of the handle 15 causes the prize bar 18 to move endwise so as to pass between the upstanding sides of the inverted V-shaped bracket 22. Further downward movement of the handle 15 causes the bar 18 to bear against the top end of the bracket 22 and thus center the suction head over the barrel as it moves downwardly to bring the barrel head which is being carried thereby into the chime of the barrel being headed. The foot lever 46 is then further depressed, thus securely clamping the head in the barrel. The suction head is next lifted upwardly, thus breaking the suction and releasing the barrel head. A suitable hoop is then placed around the top of the barrel and the foot lever 46 released, thus taking the tension off of the cable 40, thereby releasing the barrel. Raising and lowering of the suction head unit is rendered comparatively easy by reason of the counter-weights 37 which are so proportioned as to permit ready raising and lowering of the suction head unit.

Although but one specific embodiment of this invention has been herein shown and described, it is to be understood that numerous details of the construction shown may be altered or omitted without departing from the spirit of this invention as defined by the following claims.

I claim:

1. In a barrel heading machine, the combination with a supporting frame, of a suction head slidably and rotatably mounted on said frame, a guide member on said frame, a handle pivotally mounted on said suction head, and a bar pivoted eccentrically to said handle for insertion into said guide member during downward rotation of said handle to guide the suction head into registration with a barrel end during vertically downward movement of said suction head.

2. In a barrel heading machine, the combination with a supporting frame, of a suction head slidably and rotatably mounted on said frame, a guide member on said frame, operating mechanism comprising a handle and a pivot pin mounted on said suction head, a bar pivoted eccentrically to said handle, said

bar being movable by the initial rotation of said handle for engaging one end thereof in said guide, limiting means comprising a bracket on said suction head for arresting movement of said bar, said bar being engageable at its other end with said pivot pin for permitting vertically downward movement to be imparted to said suction head by the manipulation of said handle.

10 3. In a barrel heading machine, the combination with a supporting frame, of a suction head slidably and rotatably mounted on said frame, a guide member on said frame, a handle pivotally mounted on said suction head, 15 and means operatively connected with said handle including an element movable into and out of cooperation with said guide.

4. In a barrel heading machine, a support-

ing frame, a vertically disposed suction cylinder rigidly supported on said frame, having an opening therein, a sleeve slidably and rotatably mounted on said cylinder, the opening in said cylinder affording communication with said sleeve in different positions thereof, a hollow arm extending horizontally from said sleeve, a suction head carried by said hollow arm, means for lowering said suction head by causing said sleeve to slide on said cylinder, a fixed guide for controlling the vertical motion of said suction head, and said means including an element movable into and out of cooperation with said fixed guide.

Signed at St. Paul this 21st day of July, 1927.

GEORGE FREDERICKS.
